UNITED STATES PATENT OFFICE.

OPHA H. FLINT, OF HUNTINGTON, WEST VIRGINIA, ASSIGNOR TO THE OWENS BOTTLE COMPANY, OF TOLEDO, OHIO, A CORPORATION OF OHIO.

MACHINE FOR SECURING NECK WIRES TO BOTTLES.

Application filed May 7, 1927. Serial No. 189,531.

The present invention relates to improvements in means for securing neck wires to bottles and the like containers.

Considerable difficulty has been experienced in satisfactorily affixing neck wires to bottles and the like containers. It is the general practice to manually affix these wires, said wires being slipped over a bottle neck, after which operation the worker twists together the radially extended ends of the wires. These twisted ends generally are left in the position occupied following completion of the twisting operation, with the result that said ends, which are quite sharp, frequently cause serious injury to persons handling containers to which the wires are affixed. Also, it is obvious that manual attachment of neck wires means low production.

20 Machines have been conceived to attach neck wires to containers but evidently are not commercially practical, in that production by their use is no greater than with hand attaching, and for the further reason that certain of these machines are of rather complex construction and require considerable attention and manipulation of parts in their operation. Hence, manual attaching of neck wires is preferred.

25 An object of the present invention is to provide an extremely simple semi-automatic machine capable of rapidly and securely affixing neck wires to containers such as bottles, and so attaching the wires that the sharp ends are not exposed in a manner to injure the hands of persons handling the containers.

Another object of the present invention is to provide a machine in which bottles may be placed at one station together with stoppers and neck wires or perhaps the neck wires alone, properly positioned thereon, said machine operating to securely affix the wires to the bottle necks at one station by twisting the ends of the wires together; bending the twisted ends into snug contact with the bottle necks at another station, and then ejecting the bottles with the stoppers attached at a final predetermined station.

50 Other objects will be apparent hereinafter.

In the accompanying drawings:

Fig. 1 is a perspective view of the machine.

Fig. 2 is a plan view showing the manner in which bottles are brought to the neck wire twisting and bending stations simultaneously with ejection of a bottle to which the neck wire has been attached. 55

Fig. 3 is a side elevation of the machine from the side opposite that shown in Fig. 1.

Fig. 4 is a sectional view taken substantially along the line IV—IV of Fig. 2. 60

Fig. 5 is a sectional view taken substantially along the line V—V of Fig. 4.

Fig. 6 is a detail sectional view showing the wire twisting chuck just after it has engaged the ends of a neck wire, and prior to the initial twisting operation. 65

Fig. 7 is a transverse sectional view showing the jaws which operate to bring the neck wire extremities to a position permitting 70 gripping by the wire twisting chuck.

Fig. 8 is a detail perspective view of the device shown in Fig. 7.

Fig. 9 is a transverse sectional view taken along the line IX—IX of Fig. 3. 75

Fig. 10 is a fragmentary perspective view of the bottle and neck wire holder.

Fig. 11 is a detail view showing the manner in which a bottle is supported in the bottle holder, the ends of the securing wire 80 being shown twisted together.

Fig. 12 is a fragmentary detail showing the twisted ends of the securing wire bent over against the bottle neck.

Fig. 13 is a transverse sectional view taken 85 along the line XIII—XIII of Fig. 4.

Fig. 14 is a fragmentary plan view illustrating the manner in which the bottle holder operates to position one bottle so that the twisted end of the neck wire will be rolled 90 over against the outer face of the bottle while the ends of the neck wire next succeeding are being twisted together.

Fig. 15 is a detail plan view showing the means for upsetting or bending the twisted 95 ends of the neck wires.

Fig. 16 is a detail side elevation of the device shown in Fig. 15.

Fig. 17 is a sectional view taken along the line XVII—XVII of Fig. 15.

Referring to the accompanying drawings, a table 20 of substantially rectangular formation is supported at the desired elevation upon legs 21 suitably braced by cross bars 22. Suspended from said bars 22 is a motor 23 which operates the mechanism hereinafter set forth. A motor control switch 125 is arranged upon the table 20 (Figs. 1 and 2). This motor 23 drives a longitudinal shaft 24 to which it is connected by a belt and pulley drive 25 including an automatic belt tightener in the form of a small pulley 26. The end of the shaft 24 opposite said drive, mounts a small gear 27 running in mesh with a relatively large gear 28 fixed to one end of a countershaft 29 located below and at one side of the first named longitudinal shaft 24. The ratio of the gears 27 and 28 is such that the speed of rotation of the lower countershaft 29 is considerably reduced with respect to that of the other shaft, for reasons which will be apparent hereinafter.

The motor driven shaft 24 carries a sprocket 30 over which runs a sprocket chain 31 extending upwardly through an opening 32 in the table 20, the upper end of said chain being trained over a small sprocket 33, included in a neck wire twisting device. This wire twisting device comprises a sleeve or tube 34 rotatively mounted in a bearing 35 near the upper end of a standard 36 which is arranged upon the table 20. This sleeve or tube 34 is enlarged at its inner end to receive a pair of coacting chuck or wire twisting jaws 37 connected to a reciprocable rod 38 by a single pivot pin 39. These jaws 37 are normally held in spaced relation to each other by an expansion spring 40 and are held within said enlarged end of the tube 34 by a removable cap 41. The inner adjacent face 42 of the cap 41 is inclined (Fig. 6) to contact with the inclined faces of the chuck jaws 37 whereby longitudinal inward movement of the rod 38 will cause movement of the jaws toward each other to wire gripping position. A coil spring 43 encircling the outer end portion of the tube or sleeve 34 and confined between a shoulder formed on said sleeve and a disk 44 carried by said rod, operates to normally and yieldably position said rod so that the chuck jaws 37 are spaced apart. The rod 38 is periodically moved longitudinally inward to close the chuck jaws by means of a vertical rock arm 45, fulcrumed substantially at its center to a bracket 46 and having its lower end provided with a cam roll 47 running upon a continuously rotating cam 48. The upper end of said rock arm 45 engages the outer end of the chuck jaw carrying rod 38. This cam 48 is fixed to the countershaft 29 and rotates continuously therewith. Thus, it is seen that at uniformly spaced time intervals, the arm or lever 45 will be rocked about the ful-

crum 46 to shift the rod 38 and operatively position the chuck jaws as above stated.

Bottles or other similar containers with stoppers and neck wires properly positioned theron are brought in succession to a position in which the chuck jaws may operate to twist the ends of the neck wires to thereby securely attach the stoppers to the bottles. The bottles are brought into a position adjacent the chuck jaws by a holder or carrier 49 which is rotatable about a vertical axis and slidably in a horizontal plane toward and from said jaws at predetermined periods. This holder (Figs. 4 and 13) is fixed to the upper side of a slide 49 movable in guideways 50 extending longitudinally of the table 20. This slide 49 is actuated by a cam mechanism which will be described hereinafter. A cover 51 is arranged over the slide 49 and provided with a longitudinal central slot 52 through which a portion of the holder extends. This holder comprises a vertical shaft 53 having fixed thereto vertically spaced sections which rotate with said shaft and support the bottles. The lower section 54 in part supports the bottles, while the intermediate section 55 is formed with an annular series of arcuate recesses 56 to assist in properly spacing bottles about the holder. The upper section or table 57 of the holder mounts an annular series of yokes 58 (Fig. 10). These yokes are of such shape that they straddle the neck portions of the bottles just below the upper ends and are formed with transversely aligned notches 59 providing seats to receive the pivot eyes 60 of the neck wires 61. The stopper 62 carried by each neck wire 61 lies upon the upper table or section 57 during the wire attaching operations (Figs. 11 and 14). A head 63 is fixed to the upper end of the bottle holder shaft 53 for a purpose to be brought out hereinafter.

The bottle holder is intermittently rotated by a Geneva movement of the usual or any preferred type. As shown, this movement includes a relatively large gear 65 fixed to the lower end of the bottle holder shaft 53, said gear being given a rotary movement at regular intervals by engagement between slots 66 in said gear and a pin 67 fixed to a continuously rotating disk 68, said disk being mounted upon the upper end of a stub shaft 69 (Fig. 4). This stub shaft 69 is supported in a bracket 70 secured to the under side of the slide 49, and has a universal joint connection with a shaft 71. This shaft 71 is made up of telescoping sections, the lower section having a universal joint connection with a short shaft 72, which, in turn, carries a helical gear 73 running in mesh with a helical gear 74 fixed upon and rotating with the aforementioned countershaft 29 (Fig. 4). Thus, it is seen that continuous rotation of the countershaft 130

29, not only operatively positions the wire twisting chuck jaws at regular intervals, but in addition serves to bring the bottles and neck wires into longitudinal alignment with said jaws at proper time intervals.

While the Geneva movement is operating to bring the bottles in succession into alignment with said jaws, a continuously rotating cam 80 having pin and slot connection with 10 said slide 49, functions to advance the holder toward the jaws to thereby cause the ends of the neck wire to enter the space between said wire twisting jaws 37 (Fig. 6). This cam 80 is fixed to the upper end of a shaft 15 81 journalled in a bearing 82. The lower end of this shaft 81 carries a helical gear 83 running in mesh with a helical gear 84 fixed to the aforementioned countershaft 29 and rotating therewith.

20 Just prior to insertion of the ends 90 of the neck wire 61 into the twisting chuck, said ends are brought together into substantial parallel relation to each other by means of a pair of coacting jaws 91 (Figs. 7 and 25 8). Thus, the ends of the neck wire are so 30 relatively disposed that the chuck may quickly and effectively operate to twist said ends together and thereby attach the neck wire to a container. The jaws 91 are fixed to arms 93 pivoted adjacent their upper ends between transversely spaced pairs of ears 92. The arms 93 extend upwardly beyond the pivots 94 and carry rollers 95 which at 35 regular time intervals engage opposed faces of a wedge member 96 adjustably mounted upon the upper end of the chuck supporting standard 36, to thereby cause rocking of the arms 93 about the pivots 94. Such rocking causes the jaws 91 to move into operating 40 relation to each other and thereby positions the ends of a neck wire for entry into the space between said jaws by which they are twisted together. The ears 92 between which the arms 93 are pivoted are carried 45 by a bar 97 slidable through a housing 98 mounted adjacent the upper end of the standard 36 (Fig. 6), the end of said bar within the housing bearing against a coil 50 expansion spring 99 whose tension is variable by adjustment of a regulating screw 100. The other end of the ear carrying bar 97 is normally disposed adjacent the head 63 located at the upper end of the shaft 53 which supports the bottle holder. Said 55 other end includes an extensible portion 120 by which the length of the bar 97 may be varied if necessary. Thus, it is seen that when the bottle holder moves toward the chuck, the rollers 95 contact with the wedge 60 96 and cause the jaws 91 to move inwardly for the purpose above set forth. These jaws 91 are normally held in spaced relation to each other by means of a spring 101 (Fig. 7) fixed to the lower side of said 65 bar 97.

The twisted end 102 of the neck wire is bent over or upset into snug contact with the bottle neck by means of a grooved roller 103 fixed to one end of an arm 104 whose opposite end is adjustably and pivotally supported in a block 105 extending from one side of a standard 106. The roller carrying end of the arm 104 is disposed in a guide 107 which prevents up and down movement of the roller and arm, yet allows a certain degree of horizontal movement. The end of the guide in proximity to the roller 103 is formed with a substantially semi-circular recess 108 into one side of which said roller projects for engagement with the twisted 70 ends 102 of the neck wires. This roller 103 is normally yieldably held in such position by means of a coil spring 109 mounted in a holder 110 which straddles the guide 107 (Fig. 17). The tension of this spring is 75 variable by adjusting the spring retaining cap 111. The inner end of said spring bears against a wear plate or gib 112. It will be noted by reference to Figs. 14 and 15 that while one neck wire is being twisted, 80 the twisted ends of the preceding neck wire are being rolled over or upset against the container neck.

After a bottle has passed the device for upsetting the twisted ends of the neck wire, 85 it reaches a station at which it is ejected from the holder by means of a cam actuated pusher bar 113 or ejector which is moved vertically through an opening 114 in the lower section 54 of the bottle holder at predetermined time 90 intervals. This opening 114 is located inwardly from the center of the bottle supporting position on the holder so that with upward movement of the pusher rod 113, the bottle will be tilted outwardly and fall from 95 the holder by gravity into a discharge chute 115. The pusher rod 113 is raised and lowered at proper time intervals by means of a cam mechanism 116, operated by the countershaft 29 heretofore referred to as also 100 controlling the wire twisting chuck jaw and bottle holder movements.

The operation of the machine may be stated as follows:

Considering the machine to be operating, 115 bottles with neck wires properly positioned thereon are placed in the bottle holder substantially as shown in Figs. 2 and 14, in which position the divergent ends 90 of the neck wires 61 extend radially beyond the 120 holder and bottles. As the bottle approaches a position in which it will be aligned with the axis of the twisting device, the cam 80 (Fig. 4) operates to shift the holder toward said twisting device. During this movement, the 125 device including the depending swinging jaws 91 for bringing the neck wire extremities together, is operated, and is immediately followed by insertion of said extremities into the space between the wire twisting jaws 37 130

(Fig. 6). Rotation of the twisting jaws, which is continuous, tightly twists the extremities of the neck wire together, it being noted that said jaws are operatively positioned by action of the cam 48 and rock arm or lever 45 (Fig. 4). The upper end of this arm 45 moves inwardly toward the chuck jaws, causing inward longitudinal movement of the jaw carrying rod 38 and consequent movement of said jaws toward each other due to contact of the jaws with the inclined faces 42 of the cap 41 (Fig. 6). At this stage of operation, just following the completion of the twisting together of the ends 15 of the neck wire, the Geneva movement of the cam 80 operates to retract the bottle holder and remove the twisted ends of the neck wire from between the chuck jaws 37. The preceding steps are followed in applying 20 the next succeeding neck wire to the bottle and simultaneously with insertion of the extremities of the next succeeding neck wire, the twisted ends of the preceding wire engage the grooved roll 103 (Figs. 14 and 15), causing said twisted ends to be upset or bent into snug engagement with the bottle neck as shown in Figs. 12 and 14. The bottle to which the neck wire has been completely attached is moved to a third station (Fig. 14) 25 simultaneously with arrival of another bottle at the wire twisting station and is ejected from the machine. Thus, it is seen that with the exception of manual positioning of the stoppers and their securing neck wires, together with the containers in the rotating holder, the machine operations are strictly automatic.

While the foregoing description stresses more or less the utilization of the machine 40 for attaching stoppers to bottles, such a machine is well adapted for use in applying to many types of containers, neck wires or the like which are so frequently employed to secure separate closures upon the containers.

Manifestly, certain minor changes may be 45 resorted to within the spirit and scope of the appended claims.

What I claim is:

1. A machine for applying pre-formed neck wires to bottles or like containers comprising in combination, a single holder to support the bottles and neck wires, wire twisting and bending devices adjacent said holder, and automatic means to move the holder to cause simultaneous operative engagement between pairs of neck wires and said devices whereby the twisted portion of a neck wire is bent laterally against the container neck while another wire is twisted for attachment to a container.

2. A machine for applying pre-formed neck wires to bottles or the like containers comprising in combination, a rotatable bottle and neck wire holder, wire twisting and upsetting devices at one side of the holder, and

means operable at predetermined time intervals to move said holder to thereby cause successive operative engagement between a neck wire and the twisting and upsetting devices to twist the wire ends together and then bend them over against the container necks. 70

3. A machine for applying pre-formed neck wires to bottles or the like containers comprising in combination, a rotatable bottle and neck wire holder, said holder supporting the neck wires in position to be attached to the containers, wire twisting and upsetting devices, means operable at predetermined time intervals to move said holder to cause successive operative engagement between each neck wire and the twisting and upsetting devices whereby the ends of the wire are twisted together and then bent over against the necks of the containers, and automatic means to eject bottles after they have passed the upsetting device. 80

4. A machine for applying pre-formed neck wires to bottles or the like containers comprising in combination, a bottle and neck wire holder rotatable about a vertical axis, neck wire twisting and bending devices arranged at one side of said holder, and automatic means operating at predetermined time intervals to shift the holder radially, 90 causing successive operative engagement between a neck wire and said twisting and bending devices to twist the wire ends together and bend them over against the container necks. 95

5. A machine for applying neck wires to bottles or the like containers comprising in combination, wire twisting and bending devices arranged adjacent each other in the same horizontal plane, a bottle holder rotatable about a vertical axis, a slide supporting said holder, and cam means operable to move said slide at predetermined time intervals, causing movement of said holder toward and from said devices. 100

6. A machine for applying neck wires to bottles or the like containers comprising in combination, wire twisting and bending devices spaced apart in the same horizontal plane, a neck wire and bottle holder arranged at one side of said devices and movable about a vertical axis, a Geneva movement transmitting an intermittent rotary movement to said holder, and cam means operating to periodically move said holder, causing engagement between the neck wires and said devices. 115

7. A machine for applying neck wires to bottles or the like containers comprising in combination, wire twisting and bending devices spaced apart in the same horizontal plane, a neck wire and bottle holder arranged at one side of said devices and movable about a vertical axis, a Geneva movement transmitting an intermittent rotary 125

130

- movement to said holder, cam means operating to periodically move said holder, causing engagement between the neck wires and said devices, and means operating automatically 5 to eject bottles from the holder at a station beyond said devices.
8. A machine for applying neck wires to bottles or the like containers comprising in combination, wire twisting and bending devices spaced apart in the same horizontal plane, a neck wire and bottle holder arranged at one side of said devices and movable about a vertical axis, a Geneva movement transmitting an intermittent rotary 10 movement to said holder, cam means operating to move said holder toward and from said devices, causing engagement between the neck wires and said devices, and means operating automatically to eject bottles with 15 affixed neck wires at a station beyond said devices, said automatic means comprising a cam actuated pusher movable at predetermined time intervals into engagement with the bottle bottoms.
- 20 9. A machine for applying neck wires to bottles or the like containers comprising in combination, a bottle and neck wire holder, a neck wire twisting device, means for moving the holder toward and from said twisting device, means actuated by movement of the holder toward the twisting device for bringing portions of a neck wire together just prior to engagement with the twisting device, and means for bending the 25 twisted portion of the neck wire into contact with the bottle neck.
10. A machine for applying neck wires to bottles or the like containers comprising in combination, a wire twisting device, a bottle and neck wire holder movable toward and from said device to periodically insert the ends of neck wires into said twisting device, a pair of jaws arranged between said holder and twisting device, and means 30 actuated by movement of said bottle holder toward the twisting device causing the jaws to engage said neck wires and arrange the latter for engagement with the twisting device.
- 40 11. A machine for applying neck wires to bottles or the like containers comprising in combination, a wire twisting device, a bottle and neck wire holder movable toward and from said device to periodically insert the ends of neck wires into said twisting device, a pair of jaws arranged between said holder and twisting device, means actuated by movement of said bottle holder toward the twisting device, causing the jaws 45 to engage said neck wires and arrange the latter for engagement with the twisting device.
- 50 12. A machine for applying neck wires to bottles or the like containers comprising in combination, a wire twisting device, a bottle and neck wire holder movable toward and from said device to periodically insert the ends of neck wires into said twisting device, a pair of jaws arranged between said holder and twisting device, means actuated by movement of said bottle holder toward the twisting device, causing the jaws to engage and bring the ends of said neck wires together, a bending device adjacent said twisting device adapted to bend the twisted ends of the neck wires against the bottle necks, and means transmitting an intermittent rotary movement to the bottle holder 55 whereby the bottles are brought in succession to said twisting and bending devices.
- 60 13. A machine for applying neck wires to bottles or the like containers comprising in combination, a wire twisting device, a bottle and neck wire holder movable toward and from said device to periodically insert the ends of neck wires into said twisting device, a pair of jaws arranged between said holder and twisting device, means actuated by movement of said bottle holder toward the twisting device, causing the jaws to engage and bring the ends of said neck wires together, a bending device adjacent said twisting device adapted to bend the twisted ends of the neck wires against the bottle necks, means transmitting an intermittent rotary movement to the bottle holder 65 whereby the bottles are brought in succession to said twisting and bending devices, and means arranged at a station beyond the bending device to eject bottles from said holder.
- 70 14. A machine for applying neck wires to bottles or the like containers comprising in combination, a wire twisting device, a bottle and neck wire holder movable toward and from said device to periodically insert the ends of neck wires into said twisting device, a pair of jaws arranged between said holder and twisting device, means actuated by movement of said bottle holder toward the twisting device, causing the jaws to engage and bring the ends of said neck wires together, a bending device adjacent said twisting device adapted to bend the twisted ends of the neck wires against the bottle necks, means transmitting an intermittent 75 rotary movement to the bottle holder whereby the bottles are brought in succession to said twisting and bending devices, means arranged at a station beyond the bending device to eject bottles from said holder, and a single motor actuating said holder, wire twisting and bending devices, and the ejector.
- 80 15. A machine for applying neck wires to bottles comprising in combination, a sup-

port, a slide mounted for horizontal reciprocation on said support, a bottle and neck wire holder carried by the slide, means transmitting an intermittent rotary movement to the holder about a vertical axis, a neck wire twisting device arranged at one end of the path of sliding movement of said holder to engage and twist the ends of neck wires, a pair of pivoted jaws arranged between the holder and said twisting device, and means actuated by movement of the holder causing said jaws to bring the ends of the neck wires together prior to engagement of the latter with said twisting device.

15 16. A machine for applying neck wires to bottles comprising in combination, a support, a slide mounted for horizontal reciprocation on said support, a bottle holder carried by the slide, means transmitting an intermittent rotary movement to the holder about a vertical axis, a neck wire twisting device arranged at one end of the path of sliding movement of said holder to engage and twist the ends of neck wires, a pair of pivoted jaws arranged between the holder and said twisting device, and means actuated by movement of the holder causing said jaws to bring the ends of neck wires together prior to engagement of the latter with said twisting device, and means arranged adjacent said twisting device to bend the twisted ends of the neck wires into contact with the bottle necks, and automatic means to eject bottles from the holder at a station beyond said bending device.

17. A machine for applying stopper carrying neck wires to bottles comprising in combination, a bottle and neck wire holder, said holder supporting the neck wires and stoppers in position for attachment to the bottles, a wire twisting device, a wire bending device, and means operating automatically to cause relative movement between the holder and said devices to thereby effect successive operative engagement between a neck wire and said devices.

18. A machine for applying neck wires to bottles comprising in combination, wire twisting and bending devices, a rotatable bottle and neck wire holder formed to support an annular series of bottles and neck wires, and means to cause periodic relative movement between said devices and the holder to effect simultaneous engagement between the neck wires on two adjacent bottles and said twisting and bending devices.

19. A machine for applying neck wires to bottles comprising in combination, wire twisting and bending devices, a rotatable bottle and neck wire holder formed to support an annular series of bottles and neck wires, means to cause periodic relative movement between said devices and the holder to effect simultaneous engagement between the neck wires on two adjacent bottles and said

twisting and bending devices, and means to eject bottles from the holder at a station beyond the bending devices.

20. A machine for applying stopper carrying neck wires to bottles comprising in combination, a bottle and neck wire holder, said holder supporting the neck wires and stoppers in position for attachment to the bottles, means to intermittently rotate said holder about a vertical axis, means adjacent the holder to twist the ends of the neck wires together and bend said ends over against the bottle necks, means to move said holder causing engagement between the twisting and bending means and said neck wires during the intervals between rotation of the holder, and means to eject a bottle from the holder during each of said intervals.

21. A machine for applying neck wires to bottles comprising in combination, a bottle and neck wire holder, means to intermittently rotate said holder about a vertical axis, means adjacent the holder to twist the ends of the neck wires together and bend said ends over against the bottle necks, means to move said holder causing engagement between the twisting and bending means and said neck wires during the intervals between rotation of the holder, means interposed between said holder and the twisting and bending means to position the ends of a neck wire for engagement with said twisting means.

22. A machine for applying neck wires to the bottles comprising in combination, a wire twisting device including jaws movable toward and from each other to alternately grip and release the ends of a neck wire, means to rotate the jaws, a bottle and neck wire holder, means causing relative movement between said jaws and holder to effect operative engagement between said jaws and the ends of a neck wire whereby the latter are twisted together, and means to bend the twisted ends of a neck wire circumferentially of the bottle into engagement with the bottle neck.

23. A machine for applying neck wires to bottles comprising in combination, a continuously rotating wire twisting device including a pair of coacting wire gripping jaws, automatic means to move the jaws toward and from each other to alternately grip and release the ends of neck wires, means to position bottles and neck wires whereby the ends of the latter may be gripped and twisted by said jaws, and means for bending the twisted ends of the wires circumferentially of the bottle against the bottle necks.

24. A machine for applying neck wires to bottles comprising in combination, a continuously rotating wire twisting device including a pair of coacting wire gripping jaws, automatic means to move the jaws to

ward and from each other and alternately grip and release the ends of neck wires, means to position bottles and neck wires whereby the ends of the latter are gripped and twisted by said jaws, means for bending the twisted ends of the wires against the bottle necks, and means operated by movement

of a bottle and neck wire toward said jaws to position the ends of a neck wire for insertion between said jaws.

10

Signed at Huntington, in the county of Cabell and State of West Virginia, this 2nd day of May, 1927.

OPHA H. FLINT.
